US00D977959S

(12) **United States Design Patent** (10) **Patent No.:** **US D977,959 S**
(45) **Date of Patent:** **** Feb. 14, 2023**

(54) **BINDING ELEMENT**

(71) Applicants: **Piotr Konopka**, Bialystok (PL); **Marek Budnik**, Bialystok (PL)

(72) Inventors: **Piotr Konopka**, Bialystok (PL); **Marek Budnik**, Bialystok (PL)

(**) Term: **15 Years**

(21) Appl. No.: **35/512,118**

(22) Filed: **Mar. 19, 2021**

(80) **Hague Agreement Data**

Int. Filing Date: **Mar. 19, 2021**

Int. Reg. No.: **DM/214933**

Int. Reg. Date: **Mar. 19, 2021**

Int. Reg. Pub. Date: **Jul. 2, 2021**

(51) **LOC (14) Cl.** **08-08**

(52) **U.S. Cl.** **USPC** **D8/386**

(58) **Field of Classification Search**

USPC D8/349, 382, 383, 385, 354, 356, 386;
D12/223

CPC F16B 37/04
